(57) **CLAIM**

The ornamental design for an extruded door jamb with channel as shown and described.

DESCRIPTION

FIG. 1 is a top, front, right side perspective view of an extruded door jamb with channel showing my new design; FIG. 2 is an enlarged top, front, right side partial perspective view of the encircled area of FIG. 1;

FIG. 3 is a front elevation view thereof;

FIG. 4 is a left side elevation view thereof;

FIG. 5 is a right side elevation view thereof; and,

FIG. 6 is a bottom plan view thereof.

The figures show a symbolic break. Any portion of the article between the break lines form no part of the claimed design.

The left side elevation view is not shown, and there is no claim to the left side elevation view.
